UNITED STATES PATENT OFFICE

LARS BRUUN, OF DRAMMEN, NORWAY

HINGE SEAT CUTTER

Application filed June 23, 1930, Serial No. 463,241, and in Norway June 28, 1929.

The present invention relates to apparatus for chiseling of grooves, such as grooves for hinges on doors, windows and the like, by means of which apparatus the chiseling of the desired grooves may be made mechanically in a single operation.

The annexed drawings illustrate by way of example one embodiment of my apparatus.

Fig. 1 is a plan view of the apparatus, the top cover being removed.

Fig. 2 is a side view thereof.

Fig. 3 shows a cross section along the line III—III in Fig. 1.

Fig. 4 shows a section along the line IV—IV in Fig. 1.

Fig. 5 shows a section along the line V—V in Fig. 1.

Fig. 6 is a similar diagrammatical view when two chisels are used, and

Fig. 7 is a view of a hinge situated in its groove.

At the drawing 1 is a supporting member or frame, here shown as a housing having a detachable cover 2. Below the supporting member is arranged an electric motor 3, the shaft 4 of which extends into the supporting member and carries a pinion 5, preferably of raw hide or the like. At each side thereof the supporting member is provided with a handle 6.

Within the supporting member 1 are on studs 7 and 8 arranged toothed wheels 9 and 10 respectively, both of which mesh with the pinion 5. Parallel with the longitudinal axis of the supporting member 1 are arranged guides 11, 12 for the chisels 13, 14, which are V-shaped in section and arranged to be reciprocated longitudinally. Said chisels are kept into the said guides by means of members 15, 16. The guides 11, 12 are of such shape that the chisels will attain such position that their outer sides, as reckoned from the middle of the supporting member 1, stand at right angles to the plane of the supporting member.

To each of the chisels 13, 14 is secured a clamping member 17 or 18 (Figs. 1 and 4) each of which is swingably connected to one end of a rod 19 and 20 respectively; the other ends of said rods are each secured to lugs 21,

22 situated excentrically one on each of the toothed wheels 9 and 10 respectively. The lugs are so situated relatively to each other that when one chisel is moved in one direction the other chisel is moved in the opposite direction.

The front ends of the chisels 13, 14 extend outside of the supporting member 1, and are guided by a member 23 (Figs. 1 and 3) fastened to the supporting member and having grooves into which the inner portions or leaves of the chisels extend. The said member 23 prevents the chisels from tensioning upwardly when in use.

At its front end the supporting member 1 is provided with a dove-tail groove 24 which takes up and guides a slide 27. The slide 27 is provided with arms 26 and by means of a screw 25 may be adjusted at right angles to the chisels. Below said arms is arranged a support 28 provided with an opening 29 in which the front ends of the chisels 13, 14 move; said support is attached to said arms in such manner that it may be adjusted relatively to the arms in the longitudinal direction of the chisels, and in order to facilitate such adjustment the arms 21 are provided with indications 30, as shown in Figs. 1 and 2.

By adjusting the slide with the arms 26 at right angles to the chisels 13, 14 the depth of the chiselled groove may be controlled, and by adjusting the member 28 the width of the groove may be controlled. The length of the groove is regulated by moving the entire apparatus more or less sideways during the grooving operation.

When for instance grooves are to be chiseled out in a door frame 31, the apparatus is placed as indicated in Fig. 2 with the support 28 against the rabbet of the door frame or an abutment for the door frame. When the motor 3 is started the chisels are reciprocated rapidly and cut out a groove, length and depth of which is controlled by the members 28 and 26 respectively. By moving the apparatus bodily at right angle to the longitudinal direction of the chisels 13, 14 the groove may be given the desired width. The sides 33 (Fig. 6) of the groove are at

right angle to the surface of the frame 31 due to the positions of the chisels.

Fig. 7 illustrates a hinge member secured in the groove.

5 It will be understood that instead of the means here illustrated may be used eccentric discs, cam discs or any other suitable mechanism capable of imparting a rapid reciprocating movement to the chisels.

10 Having now particularly described and ascertained the nature of my said invention and in what manner the same is to be performed I declare that what I claim is:

15 1. A hinge seat cutter comprising a supporting member provided with handles, guides in the supporting member for two chisels of V-shaped cross section, said guides being so arranged that the outer branch of the V of each chisel stands at right angle
20 to the plane of the supporting member, and means for imparting a rapid reciprocating movement to said chisels.

25 2. A hinge seat cutter according to claim 1, in which the supporting member supports an electric motor, the shaft of which by means of a pinion drives two reciprocating mechanisms, each connected with one of the chisels.

30 3. A hinge seat cutter according to claim 1, in which the supporting member is provided with adjustable gauges comprising a slide, guides for said slide at the front end of the supporting member and means for adjusting said slide in said guides, arms connected to said slide in right angle to the plane thereof, a support on said arms, and means for adjusting said support in the longitudinal direction of said arms.

35 In testimony whereof I affix my signature.

LARS BRUUN.
